Patented Aug. 17, 1915.

UNITED STATES PATENT OFFICE.

JOHN WILLIAM WARBRICK, OF SPOKANE, WASHINGTON.

CANDLE-HOLDER.

1,150,405.

Specification of Letters Patent. Patented Aug. 17, 1915.

Application filed February 24, 1915. Serial No. 10,171.

To all whom it may concern:

Be it known that I, JOHN WILLIAM WARBRICK, a citizen of the United States, residing at Spokane, in the county of Spokane and State of Washington, have invented certain new and useful Improvements in Candle-Holders, of which the following is a specification.

This invention relates to improvements in candle holders for operatives such as miners whose work requires a portable light, among other equipments.

It is necessary in devices of this character to provide different means of support to accommodate different topographical exigencies, and in the present construction, the device of my invention is equipped with a hook and a spike-shaped point, the former being adapted to be hung from its supporting structure and the latter being adapted to be projected into the structure from which the candle holder is to be supported.

It is one of the objects of this invention to provide a frame into which the hook and spike point can be retracted, when the holder is carried about in the pocket of the miner, and from which the hook or spike point may be projected into an operative position for use.

It is one of the objects of this invention to provide an improved means whereby the spike point or hook may be turned into and held in retracted position or adjusted and securely held in projected positions.

Other objects and features of the invention will be more fully described in connection with the accompanying drawing and will be more particularly pointed out in and by the appended claims.

In the drawing, Figure 1 is a perspective view of my improved candle holder with the hook and point adjusted into a projected or operative position, each. Fig. 2 is a longitudinal vertical sectional view thereof with both of the supporting devices retracted into the frame. Fig. 3 is a detail detached view of a spring bar for coaction with said hook and point devices.

Like characters of reference designate similar parts throughout the different figures of the drawing.

As shown, my invention includes a frame which is formed of a strip of material, such as metal, bent upon itself to provide parallel sides 1 and 2. The bight of said frame is enlarged, as indicated at 3, to form a loop-

like guard, the purpose of which will presently appear. On side designated by 1, a candle holder 4 is mounted in which a candle or candle stick may be supported. Between the sides 1 and 2, and preferably between the ends of the sides, is movably mounted a hook comprising a shank portion 5 and a hook portion 6. The shank 5 is mounted upon a pivot 7 which extends through the frame sides 1 and 2 and through the hook shank at a point nearer side 8 thereof than side 9, and farther from the butt end 10 than from side 8. The disposition of the pivot 7 is such that when the hook is retracted into the frame, the hook portion 6 will lie within the guard 3 so that the hook portion cannot catch in the pocket of the wearer or user in such a manner as to be objectionable when the hook is out of a service position.

A spike point element 11 is disposed between the ends 12 and 13 of the sides 1 and 2 and is mounted therein by means of a pivot 14. The pivot 14 extends through the spike point nearer its side 15 than the opposite side 16 and farther from the butt end 17 than from side 15.

A spring bar 18 is pivoted between its ends by a pivot 19, to the sides 1 and 2, and the pivot 19 lies between the pivots 7 and 14. Furthermore, the pivot 19 is disposed nearer end 20 than end 21, of the spring bar 18.

Now when the parts are in the position shown in Fig. 2, there is very little tension on spring bar 18, but if the hook is projected into the position shown in Fig. 1, then the bar will be tensioned by reason of the distance between the butt end 10 and pivot 7, as compared with the lesser distance between pivot 7 and side 8. Thus tensioned, the hook will be rigidly held in a projected position notwithstanding the fact that the pivots may wear slightly loose.

The spike point 11 will usually be projected into alignment with the frame as shown in Fig. 1, but if required, the spike point will also be projected at right angles to the frame. At any rate, the end 21 will be tensioned by either position of the spike point and will serve effectively to hold the spike point in its adjusted position so that it may be forced into a stationary part to support the candle holder. Besides acting as pivots for the various parts, the rivets 7, 14 and 19 also act to hold the frame sides in rigid relation.

It is believed that the advantages and utility of my invention will be clearly understood from the foregoing description, and while I have herein shown and described one specific form of my invention, I do not wish to be limited thereto except for such limitations as the claims may import.

I claim:

1. In a candle holder for miners or the like comprising, a frame having parallel sides and an open end and having an enlarged guard at its other end, a hook having its shank pivoted between said sides to cause the hook portion to lie in said guard when retracted with the hook at right angles to the frame when projected therefrom, a spike point pivoted between said sides to project from the ends of the latter when projected and to lie between said sides when retracted, and a spring bar pivoted between said sides at a point between its ends and between the points of pivotal mounting of said spike point and hook to dispose the ends of said bar in coacting relation with the butt ends of said hook and spike point to hold either of the latter in retracted or

extended positions, substantially as described.

2. In a candle holder of the class described, a frame having parallel sides and an open end and having an enlarged guard at its other end, a spike point pivoted at the open end for projection therefrom in alignment with the frame, a hook pivoted at such distance from the guard that the hook portion will lie within the guard when retracted, the pivots of said hook and spike point being off center with respect to the sides thereof and at a greater distance from the butt ends than from the nearer sides thereof, and a pivotally mounted spring bar for coaction with the ends of said hook and spike point to hold either of the latter in projected or retracted positions, substantially as described.

In testimony whereof I affix my signature in presence of two witnesses.

JOHN WILLIAM WARBRICK.
